The ornamental design for a medical injector, as shown and described.

DESCRIPTION

FIG. 1 is an isometric view of a front, top, and right side of an ornamental design for a medical injector in a first configuration;

FIG. 2 is a front elevational view of the medical injector of FIG. 1;

FIG. 3 is a rear elevational view of the medical injector of FIG. 1;

FIG. 4 is a right side elevational view of the medical injector of FIG. 1;

FIG. 5 is a left side elevational view of the medical injector of FIG. 1;

FIG. 6 is a top plan view of the medical injector of FIG. 1;

FIG. 7 is a bottom plan view of the medical injector of FIG. 1;

FIG. 8 is a front elevational view of the medical injector of FIG. 1 in a second configuration;

FIG. 9 is a rear elevational view of the medical injector of FIG. 8;

FIG. 10 is a right side elevational view of the medical injector of FIG. 8;

FIG. 11 is a left side elevational view of the medical injector of FIG. 8;

FIG. 12 is a bottom plan view of the medical injector of FIG. 8;

FIG. 13 is a front elevational view of the medical injector of FIG. 1 in a third configuration;

FIG. 14 is a rear elevational view of the medical injector of FIG. 13;

FIG. 15 is a right side elevational view of the medical injector of FIG. 13;

FIG. 16 is a left side elevational view of the medical injector of FIG. 13;

FIG. 17 is a bottom plan view of the medical injector device of FIG. 13;

FIG. 18 is a front elevational view of the medical injector of FIG. 1 in a fourth configuration;

FIG. 19 is a rear elevational view of the medical injector of FIG. 18;

FIG. 20 is a right side elevational view of the medical injector of FIG. 18;

FIG. 21 is a left side elevational view of the medical injector of FIG. 18; and,

FIG. 22 is a bottom plan view of the medical injector of FIG. 18.
